POCKETKNIFE

Austin F. Teigen, Moorhead, Minn.

Application July 15, 1947, Serial No. 760,984

5 Claims. (Cl. 30—155)

1

The invention relates to a novel knife intended primarily for carrying within the pockets of a garment and readily useable for opening envelopes or for cutting news items and the like from papers and magazines. The object of the invention is to provide an exceptionally simple and inexpensive construction which may be expeditiously manufactured and profitably sold at a reasonable price, may be readily carried in a pocket, pocketbook or the like, without danger of the blade cutting any parts thereof, or adjacent contents of the pocket or the like, and may be quickly conditioned for use when required.

Figure 1 of the accompanying drawing is a perspective view showing the knife in readiness for use.

Fig. 2 is an inverted perspective view.

Fig. 3 is a view similar to Fig. 1, but showing the knife in readiness for carrying in a pocket or the like.

Fig. 4 is a central longitudinal sectional view as indicated by line 4—4 of Fig. 1.

Fig. 5 is a transverse sectional view on line 5—5 of Fig. 4.

Fig. 6 is a top plan view of the bottom plate.

Fig. 7 is a bottom plan view of the top plate.

Fig. 8 is a top plan view of the knife blade.

A preferred construction has been illustrated and will be rather specifically described, with the understanding, however, that within the scope of the invention as claimed, minor variations may be made. It may also here be stated that while the knife may be used in any of various positions, it has been described as if the element herein referred to as a "top plate" were always above the member which has been termed a "bottom plate," this being done to facilitate description.

The above-mentioned bottom plate is denoted at 10, said plate being formed from an elongated blank of thin sheet metal which is preferably narrowed toward its front end. This front end is turned obliquely downward as indicated at 11, and the rear end of the plate 10 is bent upwardly and inwardly to provide an overlying lug 12. Adjacent the bight joining this lug with the body portion of the plate 10, the latter is provided with an upwardly pressed detent 13. About centrally between its ends, plate 10 is formed with a short longitudinal slot 14.

An elongated top plate 15, narrower than the bottom plate 10, overlies the latter. The front end 16 of this top plate is turned obliquely upward at 16, into forwardly diverging relation with the front end 11 of the bottom plate 10, and the rear end 17 of said top plate 15 underlies the lug

12, when said plate 15 is in its normal position, in readiness for use as a knife, as seen in Figs. 1 and 4. The plate 15 is provided with downwardly and inwardly bent longitudinal flanges 18 which extend from its rear end to points somewhat in advance of its central portion, and said central portion is formed with an opening 19 communicating with the slot 14. The flanges 18 embrace the rear portion of a blade 20 which is interposed between the top and bottom plates 15 and 10, the front end 21 of said blade being disposed between the forwardly diverging plate ends 11 and 16. The rear end of the blade 20 is formed with an opening 22 aligned with the opening 19, and a pivot bolt 23 extends through these openings 19 and 22, and through the slot 14, said pivot bolt preferably having a knurled or similarly roughened nut 24. The slot 14 permits the bolt 23, the plate 15 and the blade 20 to have limited longitudinal sliding movement upon the bottom plate 10, and also allows said top plate 15 and blade 20 to be swung to a reversed position (Fig. 3). In this reversed position, the tip 21 of the blade 20 underlies the lug 12 and the front end 16 of the plate 15 overlies this lug. The rear end of the plate 15 is formed with a notch 25 which receives the above-described detent 13 (see Fig. 4), when the top plate 15 occupies its normal position, in readiness for use of the knife, said plate 15 being then held against pivotal movement by the interengagement of said detent 13 and notch 25, in addition to the clamping action afforded by the bolt 23 and nut 24. When this nut is loosened, the plate 15 may be slid forwardly sufficiently to disengage the notch 25 from the detent 13, whereupon said plate 15 may be readily reversed to the position shown in Fig. 3. The nut 24 is then again tightened.

Whenever swinging the top plate 15 to the reversed position of Fig. 3, it is swung in such a direction that the back edge of the blade 20 will enter under said lug first, overcoming danger of the blade striking the lug and dulling it, and to insure guiding of the plate end 16 into overlying relation with the lug 12 as the blade end enters under said lug, this lug is preferably provided with a downwardly bent edge 26 which acts as a cam to guide said end 16 upwardly over the lug. This cam comes into play when the edge of the blade faces in the direction shown in the drawing, and this blade position is preferable for a right-handed person. However, for a left-handed individual, the blade may be turned completely over, disposing its edge in the opposite direction. Then, in order that the plate end 16 shall be

guided up onto the lug 12 when reversing the top plate 15, said lug is formed with a second cam 21.

In using the device to open an envelope, one of the creased edges of the envelope is placed in the angle between the plate ends 11 and 16 and pierced with the tip 21 of the blade 20, after which movement of the knife along the envelope edge, will cleanly cut the latter. The tip of the blade may also be conveniently used to cut out news items and the like from papers or magazines.

From the foregoing, taken in connection with the accompanying drawing, it will be seen that novel and advantageous provision has been made for carrying out the object of the invention. However, attention is again invited to the possibility of making minor variations within the scope of the invention as claimed.

I claim:

1. A knife comprising an elongated bottom plate having its front end turned obliquely downward and having its rear end folded upwardly and inwardly to provide an overlying lug; an elongated top plate lying longitudinally upon said bottom plate and having its front end turned obliquely upward into forwardly diverging relation with said downwardly turned front end of said bottom plate, the rear end of said top plate being disposed under said overlying lug; a blade interposed between said top and bottom plates and secured to said top plate, the front end of said blade being disposed between the forwardly diverging front ends of said top and bottom plates; and a pivot connecting said top plate with said bottom plate, said pivot being located between the ends of said top and bottom plates in a position to allow reversal of said top plate to a position in which the front end of said blade will underlie said lug and said upwardly directed front end of said top plate will overlie said lug.

2. A knife comprising an elongated bottom plate having its front end turned obliquely downward and having its rear end folded upwardly and inwardly to provide an overlying lug; an elongated top plate lying longitudinally upon said bottom plate and having its front end turned obliquely upward into forwardly diverging relation with said downwardly turned front end of said bottom plate, the rear end of said top plate being disposed under said overlying lug; a blade interposed between said top and bottom plates and having its front end disposed between the forwardly diverging front ends of said top and bottom plates, said top plate having downwardly

and inwardly bent longitudinal flanges embracing said blade and securing it to said top plate, and a pivot connecting said top plate with said bottom plate, said pivot being located between the ends of said top and bottom plates in a position to allow reversal of said top plate to a position in which the front end of said blade will underlie said lug and said upwardly directed front end of said top plate will overlie said lug.

5 3. A structure as specified in claim 1; one of said plates having a longitudinal slot receiving said pivot and allowing slight forward sliding of said top plate from its normal position, the rear ends of said plates having coacting normally engaged means disengageable by said forward sliding of said top plate and normally effective to prevent pivotal movement of said top plate.

4. A structure as specified in claim 1; said lug having a downwardly bent edge constituting a cam to lift said front end of said top plate into overlying relation with said lug when said top plate is swung to reversed position.

5 5. A knife comprising an elongated bottom plate having its front end turned obliquely downward and having its rear end folded upwardly and inwardly to provide an overlying lug; an elongated top plate lying longitudinally upon said bottom plate and having its front end turned obliquely upward into forwardly diverging relation with said downwardly turned front end of said bottom plate, the rear end of said top plate being disposed under said overlying lug; a blade interposed between said top and bottom plates and having its front end disposed between the forwardly diverging front ends of said top and bottom plates, said top plate having downwardly and inwardly bent longitudinal flanges embracing said blade, said top plate and blade having aligned openings substantially midway between the ends of said top plate, said bottom plate having a short longitudinal slot communicating with said openings; and a pivot bolt extending through said openings and slot and allowing reversal of said top plate to a position in which said front end of said blade will underlie said lug and said front end of said top plate will overlie said lug; the rear ends of said top and bottom plates having coacting interengaged means releasable by forward sliding of said top plate and normally effective to hold said top plate against pivotal movement.
